(57) CLAIM

The ornamental design for a cellulite reduction tool, as shown and described.

DESCRIPTION

FIG. 1 is a bottom perspective view of a cellulite reduction tool, showing my new design;

FIG. 2 is a top perspective view thereof;

FIG. 3 is a bottom plan view thereof;

FIG. 4 is a top plan view thereof; and,

FIG. 5 is a side view thereof.

The broken lines in the figures are for environmental purpose only and form no part of the claimed design.
